UNITED STATES PATENT OFFICE.

HARVY A. DUNCAN, OF OMAHA, NEBRASKA.

DESIGN FOR A PACKAGE-TIE FASTENER.

52,563.

Specification for Design.

Patented Oct. 15, 1918.

Application filed November 3, 1917. Serial No. 200,202. Term of patent 3½ years.

To all whom it may concern:

Be it known that I, HARVY A. DUNCAN, a citizen of the United States, residing at Omaha, in the county of Douglas and State of Nebraska, have invented a new, original, and ornamental Design for a Package-Tie Fastener, of which the following is a specification, reference being had to the accompanying drawing, forming a part thereof.

The figure is a perspective view of a fastener, showing my new design.

I claim:

The ornamental design for a package tie fastener, as shown.

HARVY A. DUNCAN.
